UNITED STATES PATENT OFFICE.

ARTHUR PENTECOST, OF EAST ORANGE, NEW JERSEY, ASSIGNOR TO PIKE ADDING MACHINE COMPANY, OF ORANGE, NEW JERSEY, A CORPORATION OF NEW JERSEY.

ATTACHMENT FOR ADDING-MACHINES.

No. 910,848.

Specification of Letters Patent.

Patented Jan. 26, 1909.

Application filed September 14, 1906. Serial No. 334,662.

To all whom it may concern:

Be it known that I, ARTHUR PENTECOST, a subject of the King of Great Britain, residing at East Orange, in the county of Essex 5 and State of New Jersey, have invented certain new and useful Improvements in Attachments for Adding-Machines, of which the following is a specification.

The present invention relates to improvements in adding machines of that style or character which employ a carriage or platen carrier that is movable longitudinally to bring any of several sections of the platen into alinement with the recording or printing devices of the machine.

It has been heretofore proposed to attach to the frame of an adding machine a bar having a plurality of notches formed in its upper edge and to provide the carriage with a projecting tongue or finger adapted to enter said notches successively as the carriage is adjusted on the frame. Such a notched bar is useful when a relatively wide sheet of paper is employed to receive the record and the latter is arranged in a plurality of columns. When however a record comprising but a single column is to be produced, and a relatively narrow strip or ribbon of paper is employed considerable care is required on the 30 part of the operator to properly position the carriage on the frame.

The object of the present invention is to provide an improved space bar which is adjustable upon the frame of the machine and 35 can be quickly arranged to adapt the carriage for use with either a narrow strip of paper or with a relatively wide sheet and which will insure a proper positioning of the platen when used with a narrow paper without particular attention from the operator.

In the accompanying drawing—Figure 1 is a rear elevation of an adding machine having an embodiment of the present invention applied thereto; Fig. 2 is a plan view of the 45 carriage and space bar, with the latter in the position shown in Fig. 1; Fig. 3 is a partial plan view, showing the space bar reversed and in the position occupied when a sheet of paper is in use; and Fig. 4 is a detail view.

Referring to the drawings the platen P is mounted in a carriage supported in suitable ways on the frame of the machine to move beneath the printing devices and said carriage is held stationary in the desired relation to the printing devices by the engage-

ment of a pivotally mounted dog 2 thereon with a bar 1 supported on the frame of the machine. Said bar has its ends suitably notched to receive a pair of pins or studs 4 projecting from the frame and is normally held in engagement with said studs and prevented from moving vertically away therefrom by a pin 3 projecting rearwardly from the carriage, and across the upper edge of said bar.

In the upper edge of the bar 1 are formed a plurality of notches 6 corresponding in number to the maximum number of columns into which the record produced by the machine may be divided; and the dog 2 is 65 adapted to enter any of said notches. The space bar is also provided with an upwardly projecting stop 7 against which the dog 2 bears when the carriage is positioned for use with a narrow strip of paper. This stop 7 is 70 carried by an arm pivotally connected at one end to one face of the bar, as at 8, and having its other end connected with the bar by a suitable spring 9 which acts to hold the stop 7 above the bar. The upward movement of the stop 7 is limited by a stop pin 7^b 75 projecting from the bar 1 and about which the spring 9 extends in the embodiment of the invention shown in the drawings.

It will be understood that the lug 2 must 85 bear close against the stop 7 when the carriage is in proper position for use with a narrow strip of paper; and some trouble has been experienced by operators moving the carriage against said stop with such force as 90 to cause a slight rebound before coming to rest, with the result that the carriage would be left in a position at one side of that desired. To avoid this there is formed on the upper edge of the arm carrying the stop 7, 95 and between said stop and the spring pressed end of the arm, an inclined surface 7^a which is separated from the stop 7 by a space or notch of such size as to receive the dog 2 on the carriage. When the carriage is moved to 100 bring the lug 2 against the stop 7 the lug in passing over the inclined surface 7^a will depress said arm slightly, which, however, will immediately rise as the lug comes against the stop 7 and into alinement with the notch separating said stop and inclined surface, thus 105 positively preventing any rebound and holding the carriage in proper position.

The parts will operate in the manner just described when the space bar is arranged as 110

shown in Figs. 1 and 2 and the record is to be produced on a narrow strip or ribbon of paper, or in other words when the carriage is to be retained in a single position throughout the operation of the machine. In order to prevent the lug 2 from entering any of the notches 6 in the space bar, at the left of the stop 7 in Fig. 1, and to relieve the operator from any doubt as to the platen being in proper position when the longitudinal movement of the carriage is arrested, a strip 10 is secured to the same face of the space bar as the arm carrying the stop 7. The upper edge of this strip is flush with the upper edge of the space bar and the lug 2 on the carriage moves along said strip and is thereby prevented from entering any of the notches 6 in its travel toward the stop 7.

To adapt the carriage for use in making a record comprising several columns, and with a sheet of paper, as distinguished from a single column record on a narrow strip of paper, the carriage is moved to the left sufficiently far to bring the pin 3 and lug or dog 2 beyond the end of the space bar when the latter can be easily lifted from the supporting studs 4 and reversed, or positioned as shown in Fig. 3. In this arrangement of parts it will be seen that the carriage can be held in any desired adjustment by causing the lug 2 to enter the proper notch 6. The stop 7 and strip 10 it will be seen are on the opposite side of the space bar from the lug 2 when the parts are in the position shown in Fig. 3 and do not interfere at all with the movement or operation of the lug 2.

The lug 2 may be rocked by any suitable means. As shown, it is carried by a rock shaft extending longitudinally of the carriage and provided at one end with an operating handle or crank arm 11.

The manner of using and the advantages of the attachment will be readily understood and appreciated from the foregoing description and the drawing and it will be seen that there can be modifications of some of the features described without departing from the invention.

What is claimed is:—

50 1. In an adding machine, the combination with the frame, and a platen carriage adapted to be moved longitudinally on the frame, of an adjustable space bar adapted when in one position to coöperate with the carriage and frame to maintain said parts in a particular relation and when adjusted to a different position to maintain said parts in any of a plurality of different relations.

2. In an adding machine, the combination with the frame, and a platen carriage adapted to be moved longitudinally on the frame, of an adjustable space bar adapted when in one position to coöperate with the carriage and frame to hold the carriage stationary on the frame at a single point and

when adjusted to a different position to permit the carriage to be held stationary on the frame at any one of a plurality of points.

3. In an adding machine, the combination with the frame, and a platen carriage 70 adapted to be moved longitudinally on the frame, of an adjustable space bar adapted when in one position to coöperate with the carriage and frame to hold the carriage stationary on the frame at a single point, and 75 when adjusted to a different position to permit the carriage to be held stationary on the frame at any one of a plurality of points on opposite sides of the first said point.

4. In an adding machine, the combination with the frame, and a platen carriage 80 adapted to be moved longitudinally on the frame, of an adjustable space bar adapted to coöperate with the carriage and frame to hold the carriage from longitudinal movement and having two independent and different series of stops, whereby the positions in which the carriage may be held on the frame can be varied by adjusting said bar.

5. In an adding machine, the combination with the frame, and a platen carriage 85 adapted to be moved longitudinally on the frame, of a space bar mounted on the frame of the machine and having a stop pivotally connected therewith, a dog on the carriage 90 adapted to engage said stop, and means for engaging the dog when in contact with the stop and maintaining such contact.

6. In an adding machine, the combination with the frame, and a platen carriage adapted to be moved longitudinally on the frame and having a rearwardly extending projection, of a stop pivotally mounted on the frame of the machine and having a notch 105 adapted to receive said projection on the carriage, substantially as and for the purpose described.

7. In an adding machine, the combination with the frame, and a platen carriage adapted to be moved longitudinally on the frame and having a rearwardly extending projection, of a stop mounted on the frame and adapted to engage opposite sides of 110 said projection on the carriage.

8. In an adding machine, the combination with the frame, and a platen carriage adapted to be moved longitudinally on the frame and having a rearwardly extending projection, of a stop bar adjustably mounted on the frame of the machine and provided 120 with a plurality of notches each adapted to receive said projection on the carriage when the bar is in one position, and a stop secured to said bar and adapted to extend into the path of said projection on the carriage when 125 the bar is in another position.

9. In an adding machine, the combination with the frame, and a platen carriage adapted to be moved longitudinally on the frame, of two studs projecting from the 130

frame, a space bar having its ends extending across said studs, and a projection on the carriage adapted to bear on the space bar and hold it in contact with the studs on the frame.

10. In an adding machine, the combination with the frame and platen carriage adapted to be adjusted bodily on the frame, of an adjustable space bar adapted when in one position to hold the carriage and frame in proper relation to produce a record comprising a single column, and when in a different position to permit the carriage to be held in different positions to produce a record comprising a plurality of columns.

11. In an adding machine, the combination with the frame, the recording devices,

and platen carriage adapted to be adjusted to bring any desired section of the platen opposite the recording devices, of an adjustable bar adapted, when in one position, to hold the carriage stationary when a particular section only of the platen is in operative relation to the recording devices and, when in a different position, to hold the carriage stationary when any one of a plurality of sections of the platen is in operative relation to the recording devices.

In testimony whereof I affix my signature in presence of two witnesses.

ARTHUR PENTECOST.
